HIS ATTORNEY

UNITED STATES PATENT OFFICE

ADDISON ELIJAH KAUFMAN, OF CHICAGO, ILLINOIS

TRANSFER HOLDER

Application filed April 29, 1929. Serial No. 358,961.

This invention relates to certain novel improvements in holding devices especially adapted for removably holding a street car transfer, theatre ticket, bus coupon or the like and has for its principal object the provision of an improved construction of this character which will be highly efficient in use and economical in manufacture.

Among the several objects of this invention is to provide a device having provision for removably holding a street car transfer or ticket and other provision for releasably clamping the device to the cuff of a sleeve or other part of a garment whereby to expose the transfer or ticket for expeditious removal from the device. By the use of a device of this character the inconvenience of retaining a transfer or ticket in the hand or between the fingers until disposal is entirely eliminated as the device is so constructed as to retain the transfer or ticket in such a position where the ticket or transfer can be readily found and removed for disposal when occasion requires.

Other objects will appear hereinafter.

The invention consists in the novel combination and arrangement of parts to be hereinafter described and claimed.

The invention will be best understood by reference to the accompanying drawings showing the preferred form of construction and in which:

Fig. 1 is a fragmentary view of a cuff of a sleeve showing my invention associated therewith;

Fig. 2 is a perspective of the invention; and

Fig. 3 is a perspective view of the invention showing the cover plate in closed position.

To accomplish the many objects of my invention and to afford expeditious manufacture thereof I provide a clamp 10. This clamp 10 is preferably formed from an elongated strip of material bent centrally upon itself to form a substantial clamp of sufficient resiliency for removable connection with the cuff 11 of a sleeve or other part of a garment. To increase the resiliency of the clamp there may be provided at the bight portion a bead 12. The top plate 13 of the clamp has hingedly

connected at one edge thereof a plate 14 and embodied in this hinge connection is a coil spring 15 which acts upon the plates 13 and 14 to move the cover 14 in an open position.

The cover 14 is releasably held in the closed position upon the plate 13 by means of a pin 16 which is adapted to project into an opening 17 and lug 18 formed on the plate 13. This lug 18 is of sufficient resiliency to permit the pin to ride thereover into and from engagement in the opening 17.

In use the holding device is mounted upon the cuff 11 by means of the clamp 10. The plate 14 is disposed in an open position and the transfer or ticket 19 is placed upon the plate 13 so that a portion of the transfer or ticket will project beyond the inner end of the plate 13. The cover 14 is now pivoted into closed position upon the transfer or ticket whereby to releasably hold the transfer or ticket upon the plate 13 until it is desired to remove the transfer or ticket at which time the projecting end of the transfer or ticket is grasped between the fingers so as to afford removal of the transfer or ticket from between the plates 13 and 14 while the plate 14 is in a closed position.

It will be seen that I provide a novel holding device which at all times will removably hold a transfer or ticket or the like in a position to be disposed when required.

While I have illustrated the preferred form of construction of my invention this is capable of variation and modification without departing from the scope of this invention. I, therefore, do not wish to be limited to the precise details shown and described but desire to avail myself of such modifications and variations as come within the scope of the appended claims.

Having thus described my invention what I claim as new and desire to protect by Letters Patent is:

1. A holding device including a member bent to provide a resilient clamp, a member adapted to be disposed upon one limb of the clamp and cooperate with said limb to removably hold a transfer or the like, means for hingedly connecting said member to said

limb, and means for moving said member in an open position relative to said limb.

2. A holding device including a member providing a resilient clamp, a plate member adapted to be disposed upon a limb portion of said clamp and cooperate with said limb portion to hold a transfer or the like, means for hingedly connecting said plate to said limb portion, and means for releasably latching said plate in position upon said limb portion.

3. A holding device for a transfer or the like including a clamp adapted for connection with a portion of a garment, a plate member adapted to be disposed upon a limb portion of the clamp and cooperate with the limb portion for releasably holding the transfer, means providing a hinge connection between the plate member and said limb portion, a pin on said plate member, and a perforated lug on said limb portion adapted to cooperate with the pin for retaining the plate member in closed position upon said limb portion.

25 In testimony whereof I affix my signature.
ADDISON ELIJAH KAUFMAN.
